Claims priority, application Great Britain Nov. 14, 1967

Int. Cl. D12—14

U.S. Cl. D14—6

FIG.1

FIG.2

FIG.3

FIG.4

FIG.5

FIG. 1. Is a perspective view of a combined gear lever knob and coinholder embodying my design;

FIG. 2. is a front view of the combined gear lever knob and coinholder shown in FIG. 1.;

FIG. 3. is a view in side elevation of the combined gear lever knob and coinholder shown in FIG. 1;

FIG. 4. is a top plan of the combined gear lever knob and coinholder shown in FIG. 1; and

FIG. 5. is a bottom plan of the combined gear lever knob and coinholder shown in FIG. 1.

I claim:

The ornamental design for a combined gear lever knob and coinholder, as shown.
